UNITED STATES PATENT OFFICE.

JACOB BLOCH, OF CINCINNATI, OHIO.

MECHANIC'S APRON.

1,413,569.

Specification of Letters Patent. Patented Apr. 25, 1922.

Application filed February 3, 1921. Serial No. 442,039.

To all whom it may concern:

Be it known that I, JACOB BLOCH, a citizen of the United States, residing at Cincinnati, in the county of Hamilton and State of Ohio, have invented certain new and useful Improvements in Mechanics' Aprons; and I do hereby declare the following to be a full, clear, and exact description of the invention, such as will enable others skilled in the art to which it appertains to make and use the same.

This invention relates to wearing apparel, and more particularly to an apron designed to be used by automobilists on the road or at home in the garage when changing a tire or doing other work on a car without putting on overalls or changing their clothing. It is also adapted for use by mechanics in the shop, or butchers or grocery men in the store. The objects of the invention are to provide a simple and inexpensive apron of the character referred to that can be easily and quickly put on or taken off and secured to the wearer in position for use without using buttons and button holes or similar fastening means, and which will cover and protect the front and other portions of the body that are exposed and liable to be soiled in doing the kind of work that renders it necessary to wear an apron or the like to prevent soiling one's clothes; the rear portion of the body being left uncovered, so as to avoid unnecessary warmth in warm weather and prevent waste of material and unnecessary expense.

The invention will first be hereinafter more particularly described, with reference to the accompanying drawings, which are to be taken as a part of this specification, and then pointed out in the claims at the end of the description.

In said drawings,

Fig. 1 is a front view of an apron embodying my invention; and Fig. 2 is a rear view of the same, the sleeves being removed.

Referring to said drawings, in which the same reference letters are used to denote corresponding parts in different views, the letter A denotes the main or front portion of the apron which is preferably of such length and width as to cover completely the front part of the body of the wearer from the neck to the shoes, although it may be made shorter, if desired, and which may consist of a single piece of cloth having a substan-

tially semi-circular portion thereof at its upper end cut away to fit around the neck and provide rearward extensions a to which are sewed the front ends of shoulder pieces or yokes B, which extend rearwardly around the arm holes and are secured to the sleeves C along one edge. As shown, the shoulder pieces or yokes B extend from a point over the shoulder to a point under the arm pit where their lower ends are secured to said main or body portion A, their outer edges being slightly concave for about one third of their length and the remaining portion thereof convex, and to said concave edges are secured approximately triangular shoulder pieces or flaps D, having reduced extensions d of sufficient length to fit around the body with the two ends thereof tied together as at d¹ to hold the apron in proper position. It may be desirable, however, in some cases to shorten said extensions d, d, and provide hooks or eyes on the ends thereof for connecting them with hooks or eyes on the front of the apron, as indicated in dotted lines x, x, Fig. 1. It may also be desirable to provide clasps at the ends of the sleeves, as shown, for tightening said ends around the wrists, to insure a covering for the cuffs and prevent the latter from being soiled. The apron is also preferably provided with a pocket E, which may be divided into sections, as indicated in dotted lines, for holding mechanics' tools, etc.

I thus provide a very simple and inexpensive buttonless apron, which will completely cover and protect the front of the body from the neck to the shoes, or as far down as may be desired, and also the sleeves and shoulders, but leaving the back exposed, where no covering is required, so as to afford protection for those parts of the body which are liable to be soiled and which it is desirable to protect, and leaving uncovered those parts which are not liable to be soiled and which it is undesirable to cover, especially when the apron is used in warm weather or in a close room or warm atmosphere, and reducing the quantity of material used and the cost of manufacture to a minimum.

Having thus described my invention, what I claim as new and desire to secure by Letters Patent is:

1. An apron of the character described, comprising a main portion of sufficient length and width to entirely cover the front

of the body and extend part-way around both sides, leaving an open space at the back; the upper portion thereof being cut away so as to provide a neck opening and 5 rearwardly extending shoulder-pieces on opposite sides, yokes secured at one end to the rear ends of said shoulder-pieces and extending rearwardly and downwardly therefrom to a point under the arm pits and having 10 their lower ends secured to said main portion; arm holes being formed partly by said shoulder-pieces and partly by said yokes and sleeves secured thereto, and flaps of approximately triangular form, having 15 their edges at the base of the triangle secured to said yokes and provided with reduced portions which extend around the body to said front portion where they are secured so as to hold the apron in position.

20 2. An apron of the character described, comprising a front portion of sufficient length and width to completely cover the front of the body and extend part-way around both sides, leaving an open space at 25 the back, said portion having a neck opening at the upper end thereof and rearward

extensions or shoulder pieces the outer edges of which form a part of the arm holes and to the rear ends of which are secured the front ends of yokes which extend partway 30 around the arm holes to a point under the arm pits and having their lower ends secured to said front portion, the outer edges of said yokes being curved in continuation 35 of the curvature of those portions of the arm holes which are formed in said front part and their inner edges being concave for a portion of their length and convex the remaining portion thereof, and rearwardly and laterally projecting flaps of approximately 40 triangular form having substantially convex edges at the base of the triangle secured to the concave edges of said yokes and having reduced extensions adapted to fit around the body and secured at the front 45 of the apron.

In testimony whereof I affix my signature in the presence of two witnesses.

JACOB BLOCH.
